LIGHTING FIXTURE

Marshall S. Wideree, Northbrook, Ill., assignor to
 Benjamin Electric Mfg. Company, Des Plaines,
 Ill., a corporation of Illinois

Application June 27, 1938, Serial No. 215,966

5 Claims. (Cl. 240—147)

This invention relates to a lighting fixture, and more particularly to a dust-proof lighting fixture.

Various types of lighting fixtures have been proposed in the past which have in combination therewith a transparent bowl arranged with the reflector or canopy of the fixture in such a manner that dust may be excluded from the inner portions of the fixture. These have not been entirely satisfactory, however, since the bowl portion is generally difficult to remove when re-lamping or servicing becomes necessary, particularly when the fixture is attached to ceilings and other more or less inaccessible places.

One of the objects of this invention is to provide a lighting fixture having improved means whereby a light-transmitting bowl may be easily and quickly attached and detached with respect to the supporting canopy to provide access to the interior of the fixture for re-lamping, cleaning, and servicing.

A further object of this invention is to provide a fixture having improved means whereby the light-transmitting bowl may be suspended from the canopy when moved to inoperative position.

A further object of this invention is to provide such a construction in which the fixture is provided with an inverted dished reflector within the canopy.

Further and additional objects of this invention will appear from the following description and the appended claims.

Referring now to the drawings:

Figure 1 is an axial sectional view of a lighting fixture constructed in accordance with this invention;

Fig. 2 is a fragmentary axial sectional view of the lighting fixture showing the means whereby the bowl is suspended from the canopy; and

Fig. 3 is a side elevational view showing the hinge construction with the reflector removed from the canopy.

According to one embodiment of this invention, the lighting fixture comprises a canopy 10, a bowl portion 15, and a dished reflector 21 which is secured by a suitable means within the canopy. The bowl portion of the fixture may be secured by a flanged ring which is cut in such a manner that it may be attached to the canopy separately from the reflector by means of a plurality of suitable bayonet joints. The bowl portion may be hinged directly to the canopy by means of a suitable loop 32 which serves to suspend the bowl, when in a detached position, directly from the canopy and independently of the reflector. The canopy 10, reflector 21, and bowl 15 are so ar-

ranged that the bowl may be readily detached in order to remove the bulbs from the fixture.

Referring now more particularly to the drawings, a suitable canopy 10 is provided, within the base of which is attached a supporting cup 11 by screws or rivets 12. On the inner portion of the outwardly extending edges of the canopy, a felt gasket 13 is provided which contacts with a metal ring 14 secured on the edges of a light-transmitting bowl 15. The canopy 10 bears a plurality of downwardly extending straps 16 fastened by means of rivets 17 to the inside edges of the canopy 10 adjacent the outer peripheral portion. Each strap 16 has an inwardly extending portion 18 and an outwardly extending portion 19, the inwardly extending portion 18 having a threaded hole into which a screw 20 may be threaded in order to hold the dish-shaped metal reflector 21 in place. Consequently, the reflector 21 has a diameter somewhat less than the outer peripheral edges of the canopy 10. The outwardly extending portions 19 of the straps 16 are positioned to engage cut-out portions 22 of the flange 23 of the ring 14 on the edge of the bowl 15 in order to provide a bayonet joint connection with the ring 14.

The ring 14 is secured to the inside edges of the bowl 15 by means of suitable clips 24, each of which is locked in place by a screw 25, a threaded nut or plate 26, and a lock washer 27. A pad 28 is provided at the contact between the strap 24 and the bowl portion 15 to protect the bowl from chipping or breaking when the flanged ring 14 is firmly secured to the bowl. The ring securing straps 24 are spaced around the bowl in any desired number, and three will usually be found sufficient to secure the ring 14 in place.

The flange 23 of the ring 14 is notched or cut out at suitable intervals, said notches 22 being positioned to receive the outwardly extending portions 19 of the straps 16 attached to the canopy 10. The flange 23 has upwardly and downwardly extending lips 29 and 30, respectively, which permit the outwardly extending portion 19 of the strap 16 to be more readily guided under the flange 23 when the bowl portion 15 is placed adjacent the canopy portion 10 and twisted in the proper direction. A bayonet type joint is thus provided. The upwardly extending lip 29 which receives the outwardly extending portion 19 when the bowl 15 is tightened onto the canopy 10 is slightly deformed near its base 31 in order that the strap 16 and its outwardly extending portion 19 be locked into position when the bowl is in place. It will be observed that the bowl 15 may

thus be readily detached from the canopy 10 by a twisting motion by virtue of the bayonet joint produced by the outwardly extending portions 19 of the strap 16 attached to the canopy 10 and the corresponding portions 22 cut out from the flange 23 of the ring 14 secured to the bowl 15.

It will be further observed that, when the bowl is attached and locked in place, the ring compresses against the felt gasket 13, which may be cemented or otherwise securely fixed to the canopy 10. In order to provide a suitable suspension construction for the bowl with respect to the canopy, a wire loop 32 may be used, both ends of which may be secured to brackets 33 which are securely fastened to the flange 23 of the ring 14 on the bowl 15. When the bowl is in suspended position as in Fig. 2, the looped end 34 of the wire 32 passes over the inwardly extending portion 18 of the strap 16 attached to the canopy 10 and lies between the main body of the strap 16 and the bolt 20 employed for securing the reflector 21 to the strap 16. The wire 32 is pivotally secured to the brackets 33 so that it is freely movable in a plane corresponding to the long axis of the reflector. When the bowl portion 15 is moved toward the canopy 10, the wire 32 slides up into the space between the reflector 21 and the canopy 10 and pivots on the brackets 33 in order to fit within the space.

It will be observed that the brackets 33 to which the wire 32 is attached are spaced apart and so arranged that the bowl portion and the canopy may be joined by rotating each with respect to the other in the bayonet joints without disturbing the hinge itself. When the bowl is detached from the canopy it will swing free by means of the wire hinge. The reflector is positioned within the canopy so that the wire may readily pass through the space between the strap 16 and the reflector 21.

The reflector 21 contains a suitable hole 35 in the center through which the elongated portion 36 of a bulb 37 may be readily inserted and screwed into the socket 38 that is employed in connection with the lighting fixture. The socket 38 is attached to a suitable strap or plate 39 by means of screws 40. It is separate from the lighting fixture itself and passes through hole 40a in the supporting plate 11. The lighting fixture is attached to the strap 39 by means of suitable screws 41 inserted through the supporting cup 11 and into threaded portions of the strap. Wires (not shown) may be introduced to the light socket 38 in any desired manner. If desired, an auxiliary socket 42 may be attached to the reflector portion 21 of the lighting fixture by means of suitable screws 43 and screw plates 44. In order to provide an auxiliary light source 44a, wires (not shown) leading to the auxiliary socket 42 may be run between the canopy 10 and the reflector 21 from the main light socket 38, if desired.

It will be observed from the above description that the lighting fixture of this invention is substantially dust-proof, and the bowl may be readily disconnected from the canopy by merely twisting it in relation to the canopy. The bowl portion then swings free and clear of the canopy and reflector and permits ready re-lamping and servicing of the lighting fixture.

While a particular embodiment of this invention is shown above, it will be understood, of course, that the invention is not to be limited thereto, since many modifications may be made,

and it is contemplated, therefore, to cover any such modifications as fall within the true spirit and scope of this invention as defined by the appended claims.

5 I claim:

1. A lighting fixture comprising a metal canopy, an inverted dished reflector in said canopy, a light-transmitting bowl, and means for mounting said light-transmitting bowl underneath said reflector comprising a metal ring secured to the upper edge of said light-transmitting bowl and having an inwardly-extending flange having a plurality of circumferentially-spaced notches therein, a plurality of circumferentially-spaced brackets secured to said canopy and extending downwardly therefrom the reflector being suspended from said brackets and maintained in fixed spaced relationship to said canopy, said brackets each having an outturned terminal portion for disengageable cooperation with the circumferentially spaced notches in the bowl supporting flange, said bowl having a reduced neck portion and said metal ring lying mainly inside said reduced neck portion.

2. A lighting fixture comprising a metal canopy, an inverted dished reflector in said canopy, a light-transmitting bowl, and means for mounting said light-transmitting bowl underneath said reflector comprising a metal ring secured to the upper edge of said light-transmitting bowl and having an inwardly-extending flange having a plurality of circumferentially-spaced notches therein, a plurality of circumferentially-spaced brackets secured to said canopy and extending downwardly therefrom and having outwardly-extending lugs co-operating with said notches to form a bayonet joint connection between said light-transmitting bowl and canopy, said fixture having means for holding the light-transmitting bowl suspended from the canopy when the bayonet joint is disconnected comprising a loop having a hinge connection with said metal ring and straddling one of said brackets.

3. A lighting fixture comprising a metal canopy, an inverted dished reflector in said canopy, a light-transmitting bowl, and means for mounting said light-transmitting bowl underneath said reflector comprising a metal ring secured to the upper edge of said light-transmitting bowl and having an inwardly-extending flange having a plurality of circumferentially-spaced notches therein, a plurality of circumferentially-spaced brackets secured to said canopy and extending downwardly therefrom and having outwardly-extending lugs co-operating with said notches to form a bayonet joint connection between said light-transmitting bowl and canopy, said fixture having means for holding the light-transmitting bowl suspended from the canopy when the bayonet joint is disconnected comprising a link having a hinge connection with said bowl and having a swinging connection with said canopy when the bayonet joint is connected.

4. A lighting fixture comprising a metal canopy, an inverted dished reflector in said canopy, a light-transmitting bowl, and means for mounting said light-transmitting bowl underneath said reflector comprising a metal ring secured to the upper edge of said light-transmitting bowl and having an inwardly-extending flange having a plurality of circumferentially-spaced notches therein, a plurality of circumferentially-spaced brackets secured to said canopy and extending downwardly therefrom and having outwardly-extending lugs co-operating with said notches to

form a bayonet joint connection between said light-transmitting bowl and canopy, said fixture having means for holding the light-transmitting bowl suspended from the canopy when the bayonet joint is disconnected comprising a loop having a hinge connection with said metal ring and straddling one of said brackets, the upper portion of said loop being moved into the space between the canopy and reflector when the bayonet joint is connected.

5. A lighting fixture comprising a metal canopy, a light-transmitting bowl, and means for mounting said bowl underneath said canopy comprising a bayonet joint connection between said

bowl and canopy, said fixture having link means for holding the bowl suspended from the canopy when the bayonet joint is disconnected, said link means being housed by the canopy when the bayonet joint is connected and extended outside the canopy when the bayonet joint is disconnected and the bowl is suspended, and comprising a loop, the lower ends of which have a hinge connection with the bowl, the upper central portion 10 of the loop having a readily disengageable circumferentially slidable supporting engagement with the canopy.

MARSHALL S. WIDEROE.
